UNITED STATES PATENT OFFICE.

WALTER B. WILLIAMS, OF STAMFORD, CONNECTICUT.

DESIGN FOR A FAN.

SPECIFICATION forming part of Design No. 22,452, dated May 23, 1893.

Application filed March 18, 1893. Serial No. 466,716. Term of patent 3½ years.

To all whom it may concern:

Be it known that I, WALTER B. WILLIAMS, residing at Stamford, in the county of Fairfield and State of Connecticut, have invented and produced a new and original Design for a Fan, of which the following is a specification, reference being had to the accompanying drawing, in which—

The only figure is a plan view of a fan showing my design.

In the middle portion of the fan is a representation A of the World's Fair Grounds at Chicago, in plan view, arranged on the fan as

shown. At the right of this plan of the fair grounds is a figure B representing the landing of Columbus, and on the left hand is a figure C representing the sailing of Columbus from Spain. 15

What I claim is—

The design for a fan as shown and described. 20
